UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

BEAM CONSTRUCTION.

Application filed March 6, 1922. Serial No. 541,277.

To all whom it may concern:

Be it known that I, WALTER I. TUTTLE, a citizen of the United States, and a resident of Providence, in the county of Providence and State of Rhode Island, have invented an Improvement in Beam Construction, of which the following is a specification.

This invention relates to construction of warp beams and the like.

One of the objects thereof is to provide apparatus of the above nature of strong and durable construction. Another object is to provide a construction of the above nature which is light and thereby efficient in action, yet well adapted to meet the conditions of hardest, practical use. Another object is to provide a construction of the above nature employing wooden members with proper metal reinforcement to add strength and rigidity where they are most needed. Other objects will be in part obvious and in part pointed out hereinafter.

The invention accordingly consists in the features of construction, combinations of elements and arrangement of parts as will be exemplified in the structure hereinafter described and the scope of the application of which will be indicated in the following claims.

In the accompanying drawing in which is shown one of the various possible embodiments of this invention,

Figure 1 is an end elevation of a warp beam; and

Figure 2 is a transverse sectional view along the line 2—2 of Fig. 1 with certain parts cut away.

Similar reference characters refer to similar parts in both views of the drawing.

Referring now to the drawing in detail, there is shown in section in Fig. 2 the end construction of a warp beam, it being understood that both ends are identical, and one end only being shown in order to avoid encumbering the drawing. The barrel member or cylinder of the beam is shown at 10 and may be of any desired specific structure, such as that of a hollow wooden type built up of a number of sectors. A shaft 12 reaches the entire longitudinal extent of barrel 10 passing substantially through its center and also extends a substantial distance beyond either end of barrel 10. Inside barrel 10 and adjacent its end there is

preferably mounted a wooden abutment 11 secured to the inside surface of barrel 10 and provided with an opening at its center through which shaft 12 passes. Likewise mounted inside barrel 10 there is shown a clutch member 13 preferably secured to the face of abutment 11 as by means of screws 29. Mating with clutch member 13 is a clutch member 14 which will be hereinafter described.

Referring now to the head of the beam, there is shown resting against the end of barrel 10 a metal head member 15 which is preferably a solid metal disk of substantially the diameter of the head. Snugly contacting with the surface of disk 15 is shown a head member comprising preferably a plurality of built-up wooden elements as 16, 17 and 18. Each of these elements comprises a plurality of wooden members resting edge to edge to form a disk of diameter slightly less than that of disk 15. The three wooden disks are preferably so assembled that the grain of the wood in disks 16 and 18 is substantially at right angles to the grain in disk 17. The individual elements of disks 16, 17 and 18 may be secured together by glue or by other suitable means. The periphery of metal disk 15 is preferably flanged to extend over the peripheries of wooden disks 16, 17 and 18, and this flange extends downwardly toward the axis of the disks and then upwardly to form a groove 19 extending completely around the periphery of the head. Groove 19 thus provides a belt race through which the beam is driven. There is preferably inserted between the flange forming belt race 19 and the wooden head members a resilient filler 20, for instance of gutta percha or rawhide.

Resting against the outer surface of wooden disk 18 are shown a plurality of radially extending metal arms 21 which are preferably bent inwardly at their outer ends to support belt race 19 and are tapered to interfit about shaft 12 at the center of the head as shown in Fig. 1. A plurality of rivets 22 connect each of arms 21 to disk 15 and upon being headed into position, securely and dependably clamp the three wooden elements therebetween. Rivets 22 are preferably countersunk in arms 21 and in disk 15 to avoid projecting parts which might interfere with the operation of 110

the beam. It will be seen that a head structure built up in this manner embodies the lightness and consequent flexibility which is essential in beam construction and 5 that the same is yet dependably reinforced where reinforcement is most needed to insure a strong and substantial structure.

The complete head thus built up as above described is provided with a bore 23 at its 10 center through which shaft 12 passes. Shaft 12 is threaded as at 25 to receive a nut 26 (omitted in Fig. 1), and the end 28 is adapted to rest rotatably in suitable trunnions.

15 Referring now to clutch member 14 before mentioned, it is shown as being guided into clutch member 13 by shaft 12 passing therethrough. Clutch member 14 preferably contacts with the surface of disk 15 and is 20 provided with a pair of lugs 27 registering with openings in disk 15 and slightly entering wooden head member 16. Thus, as nut 26 is threaded on to shaft 12, the head moves along shaft 12 and head member 15 forces 25 clutch member 14 into engagement with clutch member 13 and in this manner the head and barrel members are easily assembled and a positive driving connection is made therebetween. As described above, the 30 beam is driven through the head member by means of belt race 19. The driving force is transmitted from the head through the clutch 14—13 to barrel member 10.

It will thus be seen that there is herein 35 provided an apparatus which embodies the various features of the invention, which apparatus in its action attains the various objects of the invention and is well adapted to meet the requirements of hard, practical use.

40 As many possible embodiments might be made of the above invention and as many changes might be made in the embodiment above set forth, it is to be understood that all matter herein set forth or shown in the 45 accompanying drawings is to be interpreted as illustrative and not in a limiting sense.

I claim as my invention:

1. In beam construction, in combination, a 50 barrel member, a circular metal head member resting against the end of said barrel member, a metal head member positioned substantially opposite that face of said first-mentioned head member which is remote from said barrel member comprising a plurality of radial reinforcing arms extending to points substantially opposite the periphery of said first-mentioned head member, a wooden head member built up of a plurality of sections interposed between said 55 metal head members, and means for securing together said two metal head members and said wooden head member interposed therebetween.

2. In beam construction, in combination, a 60 barrel member, a wooden head member built

up of a plurality of sections and having a diameter substantially equal to that of the head, a metal plate substantially covering that face of said wooden head member which is adjacent the end of said barrel, a plurality of metal reinforcing arms mounted upon the other face of said wooden head member extending radially from the center of the head to points substantially at the periphery of said wooden head member, and means passing through said radial arms and said wooden head member and said first-mentioned metal plate adapted to secure them together. 70

3. In beam construction, in combination, 80 a barrel member, a wooden head member built up of a plurality of sections and having a diameter substantially equal to that of the head, a metal plate substantially covering that face of said wooden head member which is adjacent the end of said barrel, a plurality of metal reinforcing arms mounted upon the other face of said wooden head member and extending radially from the center of the head to points substantially at 85 the periphery of said wooden head member, and a plurality of rivets securing each of said radial arms to said first-mentioned plate and locking said wooden head member therebetween. 95

4. In beam construction, in combination, a hollow barrel member, a member having a squared recess mounted therein and adjacent one end thereof, a head member at said end of said barrel member comprising a built-up wooden member interposed between two metal members, one of said metal members being extended to substantially encase the periphery of said wooden member to form a belt race thereon, and a member associated with said head member having a squared projection adapted to coact with said member having said squared recess. 100

5. In beam construction, in combination, a 105 barrel member, a wooden head member built up of a plurality of sections, a metal head member substantially covering one face of said wooden head member and secured thereto and having its edges laterally extended to substantially encase the periphery of said wooden head member to form a belt race thereon, and a resilient filler interposed between the periphery of said wooden head member and said belt race. 110

6. In beam construction, in combination, a 115 barrel member, a wooden head member therefor, a metal head member secured to said wooden head member and having its periphery flanged over to form a belt race, and a plurality of metal reinforcing arms secured to said wooden head member, said arms interfitting about the center of the head and extending substantially to the periphery to form a support for said belt race. 125

7. In beam construction, in combination, 130

- a barrel member, a wooden head member therefor, a metal head member resting against the face of said wooden head member adjacent the end of said barrel member and having its edge flanged over the periphery of said wooden head member to form a belt race, and metal reinforcing arms secured to the other face of said wooden member and supporting said belt race.
- 10 8. In beam construction, in combination, a barrel member, a wooden head member therefor, a solid metal head member against

the face of said wooden head member adjacent said barrel having its edges flanged over to substantially encase the periphery of said 15 wooden head member and form a belt race thereon, and a plurality of radially extending metal reinforcing arms secured against the other face of said wooden head member.

In testimony whereof, I have signed my 20 name to this specification this 18th day of Feb., 1922.

WALTER I. TUTTLE.
